UNITED STATES PATENT OFFICE.

DANIEL D. SCOTT, OF BOSTON, MASSACHUSETTS, ASSIGNOR TO MERGEN-
THALER LINOTYPE COMPANY, A CORPORATION OF NEW YORK.

LINOTYPE-MACHINE.

SPECIFICATION forming part of Letters Patent No. 757,685, dated April 19, 1904.

Application filed October 19, 1903. Serial No. 177,568. (No model.)

To all whom it may concern:

Be it known that I, DANIEL D. SCOTT, of Boston, county of Suffolk, and State of Massachusetts, have invented a new and useful Improvement 5 in Linotype-Machines, of which the following is a specification.

My invention has reference to matrices for linotype-machines—such as shown in Letters Patent Nos. 436,531, 436,532, and 557,000—10 and analogous machines. These matrices, each containing in one edge one or more matrix-cavities, are stored in a magazine, from which they are released successively in the order in which their characters are to appear in print 15 and assembled in line, the composed line being subsequently transferred to a mechanism for casting the slug or linotype against it.

The object of the present invention is to facilitate the assemblage of the matrices in the 20 line, to reduce the violence of the assembling action, and to prevent the matrices from injuring one another.

To this end the invention consists, essentially, in a matrix having its lower end tapered 25 or reduced in thickness, while the upper or body portion containing the matrix proper presents parallel outer surfaces.

It also consists in a combination of these 30 matrices with assembling devices, as herein-after explained.

In the accompanying drawings I have shown matrices in a form specially adapted for use 35 in the Mergenthaler linotype; but it is to be understood that my improvements are applicable to all circulating matrices used in linotype-machines, matrix-making machines, or analogous typographic machines.

Figure 1 represents a perspective view of 40 a matrix in accordance with my invention. Fig. 2 is a similar view looking from the opposite side; Fig. 3, a view illustrating the manner of assembling a line of matrices; Fig. 4, a perspective view showing the matrix in a slightly-modified form. Fig. 5 is a horizontal section through one end of the composed line and an incoming matrix. Fig. 6 is an edge view of my matrix in the preferred form.

Referring to the drawings, A represents a linotype-matrix consisting of a flat plate with

ears or lips *a* at the four corners and with the 59 intaglio character or matrix proper, *a'*, in one edge and distributing-teeth *c* in the upper end. It will be observed that when a series of these matrices are assembled side by side they will 55 present their characters in a common line. It is necessary that the side faces of the matrices shall fit closely together when they are assembled in line in order to prevent the entrance of molten metal between them during the casting operation. The opposite sides of the body 60 portion containing the matrix-cavity are therefore parallel. Heretofore these parallel faces have been continued to the lower end of the matrix.

My improvement consists in beveling or 65 cutting away the side face of the matrix, as shown at *b* in the several figures, thereby reducing its thickness toward the lower end across its entire width, or, in other words, giving it a tapered or wedge-like form at the lower 70 end. The inclined surface in vertical section may be flat, concave, or convex, and the reduction in thickness may begin at any suitable distance above the lower end, provided the 75 parallel surfaces remaining above are sufficient to insure the proper locking up of the matrices in the line.

The essence of the invention lies in reducing the thickness of the matrix at the lower 80 end, and it is to be understood that the extent of the reduced portion, the degree of inclination, and other details may be modified at the pleasure of the mechanic. With the exception of the reduced portion at the lower 85 end the matrices herein shown are practically identical with those now used in the Mergenthaler linotype-machines of commerce.

I prefer to employ my matrices in a machine of the ordinary Mergenthaler-type, having, as shown in Fig. 3, an inclined belt *B*, on 90 which the matrices descend successively from the magazine over the fixed guiding-surfaces *C* to a position in front of the rotary star-wheel *D*, whereby they are pushed forward laterally and added to the end of the line in 95 course of composition, the line being at the same time pushed forward in order to provide an opening for the admission of the incoming

matrices. A horizontal slide E is provided, as usual, with an upturned end to support and resist the front end of the composed line, this slide being urged constantly to the left by a spring F and retained as it advances by a friction-dog G.

When matrices of my form are employed, it is found that the lower wedge-shaped ends will enter between the end of the composed line and the star-wheel D more easily and smoothly and will assume their final position at the end of the line with a less violent action than the matrices made of uniform thickness in the ordinary way. It is also found that my matrices, having the reduced lower end, will pass from the distributor-bar at the top of the machine into the upper ends of the magazine-channels more readily, quickly, and certainly than those of ordinary form.

A font or set contains matrices of widely differing thickness, corresponding to the widths of the characters they contain. My improvement may be applied to all of the matrices in the set; but as the difficulties to be overcome are experienced mainly with the thicker matrices I propose under ordinary circumstances to bevel the thicker matrices only and use them in connection with thin matrices which are of uniform thickness from one end to the other, as shown in Fig. 3.

In constructing a set of matrices I propose to give them all, those which are beveled and those which are not, approximately the same thickness at the extreme lower end in order to give the assembling devices as nearly as possible a uniform action. When a thick matrix of ordinary form enters between the star-wheel and the end of the composed line, the effect is to advance the whole line suddenly and violently, and in practice it is found that the momentum of the line is frequently sufficient to carry it beyond the proper point, so that the space left between the end of the line and the star-wheel is excessive, which fact leads to difficulties which do not arise when my matrices are employed.

The beveling or cutting away may be carried down to a line flush with the surface of the ears a , as shown in Figs. 1 and 2. It is preferable, however, in most cases to leave the beveled end slightly thicker than the ear, as shown in Fig. 4, a second or deeper cut a^2 being made below the surface b and flush, or practically so, with the face of the ear. When the matrix thus constructed approaches the end of the composed line, the surface b will

first encounter the side of the preceding matrix and prevent the corner of the matrix from striking or battering in the thin wall of the matrix, as illustrated in Fig. 5.

It will of course be understood that in every case the parallel vertical surfaces of the matrices are to be sufficiently extensive to secure the proper locking up of the line and to permit the proper action of the expanding wedge 65 spacers or justifiers commonly employed.

It will be observed that the matrix is reduced in thickness entirely across the lower end from one edge to the other.

What I claim is—

1. A linotype-matrix having on one side a vertical face from top to bottom, and on the opposite side a face extending vertically downward for a portion of its length and gradually reduced in thickness for the remainder 75 of its length.

2. A font or series of linotype-matrices, comprising matrices of different thicknesses, corresponding to the characters in their edges, all of the matrices in the font being inclined 80 or beveled inwardly on one side toward the lower end, and all having the same or approximately the same thickness at the end.

3. A matrix for a linotype-machine, having at the lower end a reduced or beveled portion 85 b, and a recessed portion a^2 below the level of the surface b.

4. In a linotype-machine, a series of matrices differing in thickness in their body portions, the thicker matrices reduced in thickness at the lower end, in combination with a pushing device to assemble the matrices in line and advance the line, whereby substantially uniform action of the assembling devices is secured, notwithstanding the variation in the 95 thickness of the incoming matrices.

5. In a linotype-machine, the combination of thick and thin matrices, the former reduced at their lower end, in combination with the yielding resistant for the composed line, the star-wheel to assemble the matrices and advance the line, and means for delivering the matrices successively to the end of the line in advance of the star-wheel.

In testimony whereof I hereunto set my hand, this 14th day of October, 1903, in the presence of two attesting witnesses.

DANIEL D. SCOTT.
